HAIR CURLER

Charles E. Waltman, Los Angeles, Calif.

Application April 27, 1934, Serial No. 722,717

7 Claims. (Cl. 132—36)

This invention relates to a hair curler such as is employed in beauty salons for curling the hair on a woman's head. There are two principal methods of curling hair in use at the present time. According to one of these methods, the inner portion of the wisp of hair is wrapped on a spindle while in a moist condition, tightened up on the spindle, and the heating tube is then telescoped over the spindle to set the curl. In accordance with this method, it is substantially impossible to form the curl completely to the end of the wisp of hair. In accordance with another method, known as the croquignole method, the outer end of the wisp is wrapped up on a spindle or spool with the tip of the wisp against the body of the spindle, but in forming a croquignole curl it is not possible to curl the wisp of hair completely up to the scalp.

The object of this invention is to provide a simple apparatus and a simple method for enabling a curl to be formed throughout the entire length of a wisp of hair.

A further object of this invention is to provide a construction involving the use of a main spindle on which the principal portion of the wisp may be curled from a point near the scalp outwardly, and to provide an extension spindle detachably mounted on the spindle for enabling the outer end of the wisp to be formed into a croquignole curl.

The devices for this purpose usually include a pad which lies adjacent to the scalp and which is provided with means for clasping a wisp of hair within the same to be wrapped upon the spindle carried by the pad.

One of the objects of this invention is to provide improved means for attaching the spindle to the pad in such a way that the spindle can be readily disengaged from the pad after the curl has been set in the wisp.

Devices of this kind usually include a heating tube which is placed over the spindle and which is provided with electrical heating elements for heating the curl to set it. As usually constructed, the inner end of the heating tube is unattached and more or less open so as to permit steam forming from the moisture in the hair to escape from the inner end of the tube near the scalp. One of the objects of this invention, therefore, is to provide means for making a sealed connection between the inner end of the tube and the pad to prevent the escape of steam near the scalp.

A further object of the invention is to con-

struct the heating tube in such a way as to facilitate its being applied to the wrapped spindle and connected at its inner end to the pad.

Further objects of the invention will appear hereinafter.

The invention consists in the novel parts and combinations of parts to be described hereinafter, all of which contribute to produce an efficient hair curler.

A preferred embodiment of the invention is described in the following specifications, while the broad scope of the invention is pointed out in the appended claims.

In the drawing:

Fig. 1 is a side elevation of a curling device embodying my invention.

Fig. 2 is a section taken about on the line 2—2 of Fig. 1, looking toward the pad that carries the inner end of the spindle. This view particularly illustrates the means for enabling the pad to clamp a wisp of hair preparatory to wrapping the same on the spindle.

Fig. 3 is a longitudinal section taken about on the line 3—3 of Fig. 1, but upon an enlarged scale, certain parts being broken away, and this view illustrates in dotted lines the manner in which the croquignole curl is formed beyond the end of the main spindle.

Fig. 4 is a section taken on the line 4—4 of Fig. 3, certain parts being broken away and further illustrating the detachable connection between the inner end of the spindle and the pad.

Fig. 5 is a cross section on the line 5—5 of Fig. 3, and particularly illustrating details of a ratchet connection or one-way drive connection that enables the spindle to be rotated in a direction to tighten the curl, but which prevents the spindle from rotating backwardly thereafter.

Fig. 6 is a cross section on the line 6—6 of Fig. 3, and particularly illustrating details of the outer spindle.

Fig. 7 is a longitudinal section through a clamp of simple construction which I use with the curling device for clamping the wisp temporarily at the point where it leaves the outer end of the main spindle.

Fig. 8 is a cross section through the pad and a longitudinal section through the heating tube, indicating the wrapped wisp on the spindle and lying within the tube.

Fig. 9 is a cross section on the line 9—9 of Fig. 8, and further illustrating details of the heating tube.

Fig. 10 is a side elevation illustrating a joint

which may be employed for constructing the spindle of detachable sections of the same diameter.

5 Before proceeding to a more detailed description of the invention, it should be stated that the spindle is preferably constructed of a main section or main spindle, and an outer spindle or extension. The main spindle is detachably secured to a pad which clamps the wisp of hair.

10 In practicing the method, the wisp of hair is wrapped in a helix on the main spindle so as to leave a portion of the wisp extending beyond the outer end of the main spindle. At this point the wrapped wisp is clamped to the spindle and I then wrap the outer portion of the wisp on the outer spindle, starting with the tip of the wisp against the body of the outer spindle. This outer portion of the wisp is rolled up in this way on the outer spindle by rolling the outer spindle on the wisp in the same direction in which the curl has been wrapped on the main spindle. The outer spindle is then secured to the outer end of the main spindle. A ratchet connection is provided at the inner end of the 20 main spindle where it attaches to the pad and a ratchet connection is also provided between the outer spindle and the main spindle. After the entire wisp has been curled, as described, I then tighten up the entire wisp by rotating the outer spindle in a forward direction. This tightens the outer portion of the wisp on the outer spindle to form a tight croquignole curl and it also tightens the "spiral" curl that is formed on the main spindle.

30 35 After the complete curl has been set by means of a heating tube slipped over the spindle, the main spindle is detached from the pad. In this connection it should be understood that when the curl is tight on the main spindle it is hardly possible to rotate it any further in a tightening direction. For this reason I provide a special detachable connection which enables the inner end of the spindle to be detached from the pad by rotating the spindle in a backward direction. That is to say in a direction opposite to that in which the spindle is rotated to tighten the curl on it.

40 45

I also prefer to provide a heating tube of special construction, enabling it to form a sealed joint with the pad, thereby preventing steam forming within the tube from passing out of the tube near the scalp.

The main spindle may be formed of a single piece or, if desired, it may be formed of several telescoping sections. If desired, instead of forming such telescoping section, I may form it of several jointed sections of equal diameter. By constructing the main spindle in sections in this way, it is possible to use a spindle of a length that adapts it readily for operation with the particular length of wisp of hair that is to be curled. If a spindle of telescoping sections is employed they may be telescoped as far as desired so as to produce a relatively short spindle. Where the main spindle is made of disconnectible jointed sections, these sections may be made short and as many of these sections may be used as desired to give the main spindle the desired length.

70 Referring more particularly to the parts, and especially to Figs. 1 to 6, 1 indicates the main spindle which, as illustrated, comprises three telescoping sections 1a, 1b and 1c. These telescoping sections have grooves 2 with which ribs
75 3 cooperate to prevent relative rotation of the

three sections with respect to each other. Inner section 1a carries a head 4 which is detachably connectible to a pad 5. The pad 5 comprises a center plate 6 preferably formed of metal and provided on each side with a bakelite plate 7 beyond which a base-plate 8 is provided of cork, or similar material. The center plate 6 is provided with an offset boss 9 in which a socket 10 is formed. This socket has an interlocking connection with the head 4. Any suitable means may be provided for this purpose. In the present instance, the socket 10 comprises a central opening 11 having a plurality of radial notches 12 which are spaced equidistant around its circumference. The head 4 is provided with a plurality of radial tongues 13 which are spaced like the notches 12 and which can pass through the notches, after which a rotation through an angle 45° will bring the tongues 13 out of alignment with the notches 12 and lock the head in position. If desired, a stop 14 may be provided for limiting the rotation of the head in its locking direction.

The inner end of the section 1a slips over the head 4, and between the head 4 and the inner section 1a a ratchet connection is provided that will permit rotation of the section 1a on the head 4 in one direction only. Any suitable one-way drive connection may be employed. I prefer, however, to employ a ratchet connection 25 constructed as illustrated in Fig. 5. This ratchet connection is formed by producing a circumferential groove 15 in the head 4, in which is mounted a small arcuate strip 16 of spring material that tends by its resiliency to 30 expand against the inner face of the section 1a. One end of this strip or tongue 16 is anchored as at 17 to the head 4. This strip 16 will permit rotation of the section 1a in an anti-clockwise direction, but will not permit rotation in the 35 other direction. However, this direction is unimportant, so long as the connection is constructed so as to permit rotation in one direction only. 40

The pad 5 is formed of two sections 5a and 5b which are pivotally connected on a pivot pin 18 (see Fig. 2).

The section 5b is formed with a deep notch 19 and the opposite section 5a is formed with a deep notch 20. These notches are in alignment with each other so that in the clamping position of the section 5a and section 5b there is a small opening 21 through which the wisp of hair passes and in which it is clamped. The sections 5a and 5b are constructed so as to enable the size of this opening 21 to adapt itself to the quantity of hair in the wisp. For this purpose the section 5b may be provided with a spring 22 to cooperate with a rack 23 on the other section 5a, said rack having inclined teeth to cooperate with the bent tip of the spring 22. The device includes an outer spindle 24 which includes a tubular body 25 with an integral collar 26 at its inner end, and a sliding collar 27. The outer end of the tubular body 25 is formed with a flat head 28 to enable the outer spindle to be rotated. The inner end of the tubular body 25 extends beyond the collar 26 so as to form a neck 29 which can be received in the outer end of the outer section 1c of the main spindle. At this point a ratchet connection 30 is formed, which is constructed in the manner illustrated in Fig. 5 and in such a way that it will permit relative rotation of the outer spindle 24 in the same direction as the ratchet connection 30.

tion in the head 4 will permit rotation of the inner section 1a upon it.

The collar 26 is preferably provided with two oppositely disposed notches 31 for a purpose which will appear hereinafter and the collar 27 may also be provided with similar oppositely disposed notches 32 (see Fig. 6).

The bakelite plate 7 on the outer side of the pad is provided with an integral tubular neck 33 the outer end of which is provided with an outwardly projecting flange 34. This is for the purpose of forming a connection to the inner end of the heating tube 35. The heating tube 35 is preferably formed of two sections 35a and 35b having a hinge connection 36 between the same, and provided with a detachable fastener 37 for securing the two sections in a closed position.

At the inner end of the heating tube 35 two opposite disposed socket members 38 are provided which carry two sections 39 of a yielding washer of soft material, such as felt. The inner end of each socket member 38 is formed into a flange 40 to hook over the flange 34 on the tubular neck 33. In this way the open tube can be hooked over the flange 34. In doing this the washer 39 will seal the inner end of the tube and keep steam from passing out of the tube adjacent the pad.

The heating tube 35 has an inner wall 42 and an outer wall 43 forming an annular chamber 44 in which the heating element 45 is located, the ends of said element being attached to insulating conductors 46 and 47 which may be attached to the heating element (see Fig. 9).

The inner wall 42 of the heating tube has an extension 48 that has a contracted orifice 49 that may be closed by a suitable plug 50.

In Fig. 7 I illustrate a metal clamp 51 of simple construction, including a spring 52 and clamping jaws 53 with handles 54 that may be pressed together to separate the jaws.

In Fig. 10 I illustrate a main spindle formed of two sections 55 and 56 connected together by a joint 57. This joint comprises a sleeve formed rigid with the part 56 and having a tongue and groove connection as illustrated at 58 with the end of the section 55. This tongue and groove connection enables rotation to be imparted from section 56 to the section 55.

Instead of employing a telescoping main spindle 1, I may provide a spindle composed of sections, such as the sections 55 and 56 and connected by a joint such as the joint 57.

In using the curler, a wisp 59 of hair is clamped in the opening 21 and this wisp is then wrapped in a "spiral" curl on the main spindle 1 as indicated in Fig. 8. The wisp should be long enough so that when the outer end of the main spindle is reached there will still be an outer portion 60 (see Fig. 3) of the wisp which has not been wrapped on the main spindle. The outer spindle 24 is then applied, as indicated by the dotted lines in Fig. 3. That is to say, the tip 61 of the outer portion 60 is placed on the body 25 of the outer spindle and the outer spindle is then rotated as indicated by the arrow in Fig. 3 to wrap the outer portion 60 of the wisp on the outer spindle. The direction of this wrapping should be the same as the direction in which the wisp 59 is coiled on the main spindle 1.

Before starting to wrap the outer portion 61 of the wisp on the outer spindle, the clamp 51 should be used to secure the curl to the outer end of the main spindle, as indicated in Fig. 3.

The wrapping of the outer portion 60 of the

wisp on the outer spindle is to produce a croquignole curl and when this wrapping operation is nearly completed the outer portion 60 of the wisp is slipped into one of the sockets or notches 31 in the collar 26 and the wrapping of the outer portion 60 of the wisp on the outer spindle 24 is completed by means of the flat head 28. As the outer spindle is rotated in this way it will at first rotate on the main spindle and as the croquignole curl is being tightened, the loose collar 27 is shoved down toward the collar 26 to clamp the croquignole curl in place and produce a shorter curl. Soon after the croquignole curl becomes tight, the main spindle will commence to rotate on the head 4 and this will tighten the "spiral" curl that is formed on the main spindle.

After the entire length of the curl has been tightened-up in this way the heating tube 35 is applied over the spindle carrying the tight curl. In doing this the catch 37 should be released so as to enable the tube to be opened up and applied laterally over the spindle. In doing this, the socket members 38 are made to engage over the flange 34 to lock the inner end of the tube to the pad.

Of course after the entire curl has been tightened-up, the clamp 51 is removed before applying the heating tube.

In forming the "spiral" curl on the main spindle, it should be understood that the collar 26 can be moved inwardly as desired to reduce the length of the main spindle to adapt it to the length of the wisp and to enable the outer portion 60 of the wisp to be of any length desired in forming the croquignole curl.

The notches 32 in the loose collar 27 enable the croquignole curl to be tightened-up. This is accomplished by placing the tip of the wisp in the notch and pressing it with the thumb against the edge of the notch while rotating the collar on the tubular body 25.

It is understood that the embodiment of the invention described herein is only one of the many embodiments this invention may take, and I do not wish to be limited in the practice of the invention, nor in the claims, to the particular embodiment set forth.

What I claim is:

1. In a curling device for curling hair on one's head, the combination of a pad to lie adjacent the head, said pad having means for clamping a wisp of hair, a main spindle, means for detachably securing the inner end of the same to the pad, a ratchet device associated with the main spindle adjacent the pad and permitting rotation of the main spindle in one direction only to enable the wisp of hair to be wrapped around the main spindle and tightened thereon, an outer spindle, a ratchet device between said outer spindle and said main spindle permitting relative rotation of the outer spindle on the main spindle in the same direction that is permitted by the first-named ratchet device, said parts cooperating to enable the wisp of hair to be wrapped in a helix on the main spindle, and enabling the outer end of the wisp to be wrapped in a roll on the outer spindle with the tip of the wisp disposed inward, the outer end of said outer spindle having means for rotating the same, thereby enabling the roll on the outer spindle to be tightened, and the helical curl on the main spindle to be tightened.

2. In a curling device for curling hair on one's head, the combination of a pad to lie

adjacent the head, said pad having means for clamping a wisp of hair, a main spindle, means for detachably securing the inner end of the same to the pad, a ratchet device associated with the main spindle adjacent the pad and permitting rotation of the main spindle in one direction only to enable the wisp of hair to be wrapped around the main spindle and tightened thereon, an outer spindle, a ratchet device between said outer spindle and said main spindle permitting relative rotation of the outer spindle on the main spindle in the same direction that is permitted by the first-named ratchet device, said parts cooperating to enable the wisp of hair to be wrapped in a helix on the main spindle, and enabling the outer end of the wisp to be wrapped in a roll on the outer spindle with the tip of the wisp disposed inward, the outer end of said outer spindle having means for rotating the same, thereby enabling the roll on the outer spindle to be tightened, and the helical curl on the main spindle to be tightened, said outer spindle having a collar at its inner end with a notch therein for receiving the wisp of hair that extends beyond the end of the main spindle.

3. In a curling device for curling hair on one's head, the combination of a pad to lie adjacent the head, said pad having means for clamping a wisp of hair, a main spindle, means for detachably securing the inner end of the same to the pad, a ratchet device associated with the main spindle adjacent the pad and permitting rotation of the main spindle in one direction only to enable the wisp of hair to be wrapped around the main spindle and tightened thereon, an outer spindle, a ratchet device between said outer spindle and said main spindle permitting relative rotation of the outer spindle on the main spindle in the same direction that is permitted by the first-named ratchet device, said parts cooperating to enable the wisp of hair to be wrapped in a helix on the main spindle, and enabling the outer end of the wisp to be wrapped in a roll on the outer spindle with the tip of the wisp disposed inward, the outer end of said outer spindle having means for rotating the same, thereby enabling the roll on the outer spindle to be tightened, and the helical curl on the main spindle to be tightened, a tube for carrying a heating element to be applied over both spindles with the wisp wrapped thereupon, with means at the inner end of the heating tube for securing the same to the pad.

4. In a curling device for curling hair on one's head, the combination of a pad to lie adjacent the head, said pad having means for clamping a wisp of hair, a main spindle, means for detachably securing the inner end of the same to the pad, a ratchet device associated with the main spindle adjacent the pad and permitting rotation of the main spindle in one direction only to enable the wisp of hair to be wrapped around the main spindle and tightened thereon, an outer spindle, a ratchet device between said outer spindle and said main spindle permitting relative rotation of the outer spindle on the main spindle in the same direction that is permitted by the first-named ratchet device, said parts cooperating to enable the wisp of hair to be wrapped in a helix on the main spindle, and enabling the outer end of the wisp to be wrapped in a roll on the outer spindle with the tip of the wisp disposed inward, the outer end of said outer spindle having means for rotating the same, thereby

enabling the roll on the outer spindle to be tightened, and the helical curl on the main spindle to be tightened, a heating tube for carrying a heating element, said heating tube having two sections hinged together, said sections having socket members at their inner ends and said pad having a substantially circular flange projecting outwardly from its face to interlock with the socket members to secure the heating tube to the pad.

5. In a curling device for curling hair on one's head, the combination of a pad to lie adjacent the head, said pad having means for clamping a wisp of hair, a main spindle, means for detachably securing the inner end of the same to the pad, a ratchet device associated with the main spindle adjacent the pad and permitting rotation of the main spindle in one direction only to enable the wisp of hair to be wrapped around the main spindle and tightened thereon, an outer spindle, a ratchet device between said outer spindle and said main spindle permitting relative rotation of the outer spindle on the main spindle in the same direction that is permitted by the first-named ratchet device, said parts cooperating to enable the wisp of hair to be wrapped in a helix on the main spindle, and enabling the outer end of the wisp to be wrapped in a roll on the outer spindle with the tip of the wisp disposed inward, the outer end of said outer spindle having means for rotating the same, thereby enabling the roll on the outer spindle to be tightened, a heating tube for carrying a heating element, said heating tube having two sections hinged together, said sections having socket members at their inner ends and said pad having a substantially circular flange projecting outwardly from its face to interlock with the socket members to secure the heating tube to the pad, and a washer of yielding material composed of two sections received in said socket members respectively, for sealing the connection between the inner end of the heating tube and the pad.

6. In a curling device for curling hair on one's head, the combination of a pad to lie adjacent the head, said pad having means for clamping a wisp of hair, a main spindle, means for detachably securing the inner end of the same to the pad, a ratchet device associated with the main spindle adjacent the pad and permitting rotation of the main spindle in one direction only to enable the wisp of hair to be wrapped around the main spindle and tightened thereon, an outer spindle, a ratchet device between said outer spindle and said main spindle permitting relative rotation of the outer spindle on the main spindle in the same direction that is permitted by the first-named ratchet device, said parts cooperating to enable the wisp of hair to be wrapped in a helix on the main spindle, and enabling the outer end of the wisp to be wrapped in a roll on the outer spindle with the tip of the wisp disposed inward, the outer end of said outer spindle having means for rotating the same, thereby enabling the roll on the outer spindle to be tightened, and the helical curl on the main spindle to be tightened, and a collar loose on the outer spindle and movable toward the first-named collar for forcing the curl on the extension spindle against the first-named collar.

7. In a curling device for curling hair on one's head, the combination of a pad to lie adjacent the head, said pad having means for clamping a

wisp of hair and having a socket, a main spindle having a head at its inner end with means for detachably securing the same in said socket, a ratchet device mounted between the main spindle and said head for permitting rotation of the main spindle on said head in one direction only, said parts cooperating to enable a wisp of hair

clamped in the pad to be wrapped around the main spindle, and means mounted on the outer end of the main spindle for rotating the same in the direction permitted by the ratchet device to tighten the curl on the spindle.

5

CHARLES E. WALTMAN.
